UNITED STATES PATENT OFFICE.

CARL LOTT, OF ZURICH, SWITZERLAND.

COMMUTATOR MOTOR WITH SWITCHING ARRANGEMENT FOR THE ROTOR WINDINGS.

Application filed March 11, 1926. Serial No. 94,080.

To all whom it may concern:

Be it known that I, CARL LOTT, a citizen of the Republic of Switzerland, residing at Zurich, in the Republic of Switzerland, have invented new and useful Improvements in Commutator Motors with Switching Arrangements for the Rotor Windings, for which applications have been filed in Switzerland, November 7, 1924; Germany, September 9, 1925; Great Britain, September 15, 1925; Austria, September 25, 1925; Czechoslovakian Republic, October 17, 1925; France, October 17, 1925; Belgium, October 17, 1925; Italy, November 5, 1925; Spain, November 6, 1925; Sweden, November 6, 1925; and of which the following is a specification.

It is common to provide the rotor of a motor with two windings and two commutators in order to use one and the same rotor, for instance for two different tensions. These arrangements cannot be used on the grounds of economy since the wear and power requirements of the two commutators are too great and in addition the machine is too long. The purpose of the present invention is to overcome these disadvantages. For this purpose the machine is provided with a switch arrangement in order to enable the rotor to be set for the tension in question, the connection between the commutator and rotor winding being so made by means of the switch arrangement that the coils are either connected in series or groupwise in parallel.

An embodiment of the invention in a rotor with a lap winding is shown by way of example in the accompanying drawings.

Figures 1 to 3 show three different connections of the rotor winding.

Figure 4 is an elevation of the switch arrangement seen from the commutator side.

Figure 5 is an axial section of Figure 4.

In Figures 4 and 5, 1 is a ring of insulating material on which are secured contact springs 2, which bear on the margin 3 of the commutator 4 and make electric contact each with one segment thereof. The ring is provided with as many contact springs as the commutator has segments. A connecting wire 11 is soldered to each contact spring which it connects with the finishing end of one coil of the rotor winding. The commencing end of each rotor coil is connected with a collector segment through a conductor 14. The ring 1 is rotatably held

on the margin 3 of the commutator 4 by the contact springs 2 and the plate 5 which are located at the opposite faces of the ring 1. The plate 5 is secured to the ring 1 by a screw 10. The plate 5 acts at the same time as an indicator of the setting of the ring in relation to the disc 6, having an indicating opening 9 through which setting numbers 15 on the disc are seen. 7 and 8 are stops to limit the rotation of the ring. The contact springs are secured to the ring by rivets 12.

Figure 1 shows diagrammatically the connection at setting "1" of the switch arrangement, in which the connections are such that the finishing end of each coil is electrically connected with the commencement of the next, all the coils thus being connected in series in the usual way. If now the ring 1 is turned to position "2", thus moving the ends of the contact springs bearing on the commutator one segment further on, the finishing ends of the coils are connected no longer with the commencement of the next, but with the next but one coil (Figure 2). There is formed in this way a winding with two groups, of which the coils are connected among themselves in series, but the groups themselves in parallel. If the switch arrangement is turned to position "3", the contact springs being moved therefore over two segments, three parallel connected groups of coils in series are formed. The brush thicknesses are so designed corresponding to this third position, that the current can flow simultaneously through all three, the cross section of the winding being in this way increased two-fold for position "2" and three-fold for position "3", the ohmic resistance decreased two or three fold thus enabling the use of a tension decreased approximately in proportion.

The number of commutator segments is advantageously so designed that it is divisible without remainder by the ordinal numbers of all the different connections; that it is divisible when for example a series of four different connections are to be possible, by 2, 3 or 4 without remainder, for example therefore, 12, 24, 36, 48 and so forth.

Advantageously the stator of a machine with a rotor switching arrangement of this kind is provided with a tapped winding in order to suit the stator field to the rotor field.

Having now particularly described and ascertained the nature of my said invention

and in what manner the same is to be performed, I declare that what I claim is:—

1. A commutator motor, comprising, in combination, a commutator with a projecting margin, a rotatable ring surrounding the margin, a number of contacts, equal to the number of the commutator segments, secured to the ring and bearing on the margin, each of these contacts being electrically connected 10 to one end of a rotor coil, the other end of which is electrically connected to a commutator segment.
2. A commutator motor, comprising, in combination, a commutator with a projecting margin, a rotatable ring surrounding the margin, a number of contacts, equal to the number of the commutator segments, secured to the ring and bearing on the margin, each of these contacts being electrically connected 15 to one end of a rotor coil, the other end of which is electrically connected to a commutator segment, and a disc on which the rotatable ring is held by means of a plate secured to the ring.
3. A commutator motor, comprising, in combination, a commutator with a projecting margin, a rotatable ring surrounding the margin, a number of contacts, equal to the 20

number of the commutator segments, secured to the ring and bearing on the margin, and 30 a disc on which the rotatable ring is held by means of a plate secured to the ring, and forming an indicator, which shows the setting for the time being of the connections.

4. A commutator motor, comprising, in combination, a commutator, a rotatable ring surrounding the commutator, a number of contacts secured to the ring and bearing on the commutator, each of these contacts being electrically connected to one end of a rotor 35 coil, the other end of which is electrically connected to a commutator segment.

5. A commutator motor, comprising, in combination, a commutator, a rotatable ring surrounding the commutator, a number of 40 contacts, equal to the number of the commutator segments, secured to the ring and bearing on the commutator, each of these contacts being electrically connected to one end of a rotor coil, the other end of which 45 is electrically connected to a commutator segment.

In testimony whereof I have signed my name to this specification.

CARL LOTT.
